UNITED STATES PATENT OFFICE.

FREDERICK DREYER, OF CHICAGO, ILLINOIS.

CAN OPENER.

Application filed January 18, 1926. Serial No. 81,945.

The present invention relates to improvements in can openers, and has particular reference to a novel can opener for removing the cover by cutting the side of the can.

5 Prior can openers used to cut the cover of the can leave jagged edges which are likely to cut the hand, leave the end rim which hinders emptying the contents of the can, and cannot be moved continually in one 10 direction, hence producing small chips which may fall into the contents, and hindering the speed and ease of the cutting operation. This is true also of can openers of the above type having rotary knives since the latter 15 tend to come out of the metal and must therefore be moved back and forth. The primary object of the present invention is to correct these difficulties by providing a new and improved can opener which removes 20 the cover and the rim, in which the knife is held securely in cutting position, and which cuts continually. By cutting the side instead of the cover of the can, the structure when partially cut does not become weakened enough to retard the cutting operation.

Another object is to provide a novel can opener which is simple and inexpensive in construction and which is easy to manipulate.

Further objects and advantages will be 30 come apparent as the description proceeds.

In the accompanying drawings, Figure 1 is a view showing a fragment of a can in section and a side elevation of a can opener embodying the features of my invention in cutting position.

Figure 2 is a fragmentary view of the lower side of the can opener, the knife being shown in inoperative position.

Fig. 3 is a fragmentary plan view.

40 Fig. 4 is a sectional view taken along line 4-4 of Figure 1.

Fig. 5 is a sectional view taken along line 5-5 of Figure 1.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

55 Referring more specifically to the drawings, I have shown part of an ordinary can

having a cylindrical wall 6 and a cover or end wall 7. These walls are joined by a seam forming the usual end rim 8.

The can opener comprises a supporting 60 bar or rod 9 on which a carrier 10 supporting a suitable knife 11 is slidably mounted. One end of the bar 9 is provided with a handle 12, and the other end thereof is bent at right angles and formed with a sharp 65 prong 13 substantially parallel thereto. The prong 13 is adapted to be punched through the center 14 of the end wall 7 of the can to provide a pivot for the bar 9. When the bar 9 is lowered into position next to the end 70 wall 7, the prong 13 being in an offset plane, will underlie or hook beneath the wall to maintain the pivot during the cutting operation.

The carrier 10 consists preferably of a 75 piece of sheet metal bent about the bar 9, and is cut away near its forward end as indicated at 15 in the top and one side. A depending lug 16 is struck down at the forward end of the under side of the carrier 10, 80 and is adapted to fit over the inside of the rim 8 of the can to correctly position the carrier relative thereto. The lug 16 is slightly curved to conform approximately to the curvature of the rim 8.

85 The knife 11 preferably consists of a hardened metal disk having a sharp beveled periphery. This disk is rotatably mounted on a stud or pin 17 depending from the forward end of a lever 18. The latter is pivotally mounted on another stud or pin 19 at the under side of the carrier 10. The forward end of the lever 18 is stamped downwardly at 20 to position the knife 11 below the rim 8 when the carrier 10 rests on the latter. Struck up from one side of the forward end of the lever 18 is a stop lug 21. This lug is adapted to engage one side of the bar 9 through the space cut in the carrier 10 at 15 to hold the cutter 11 in cutting 100 position directly beneath the carrier during the cutting operation. Struck up from the rear end of the lever 18 and the side opposite the lug 21 is an arm 22 which is adapted to be actuated manually to pivot 105 the cutter 11 into operative position. The pivot 19 of the lever 18 is located at a distance from the lug 16 such that upon pivoting the cutter 11 into operative position, the latter will draw said lug against the inside 110 of the rim 8 and will pierce the side wall 6 of the can. The upper end of the lug 21 is

bent to extend over the bar 9 when the cutter 11 is in operative position to prevent the latter from being forced downwardly away from the carrier 10.

5 The operation will be clear from the foregoing description, and briefly stated is as follows: With the bar 9 in a vertical position, the prong 13 is punched through the center 14 of the cover. The bar 9 is then lowered, thereby hooking the prong 13 beneath the cover 7, and positioning the bar across the rim 8. The carrier 10 is adjusted on the bar 9 to position the lug 16 over the rim 8. The arm 22 is now pressed toward the bar 9 to pivot the cutter 11 into operative position which is defined by the lug 21, thereby piercing the side of the can just below the rim 8. The bar 9 is then pivoted around the can in a direction tending to 20 maintain the knife 11 in cutting position. A smooth and continuous cut results. The cover is quickly removed without leaving a jagged edge and without forming chips which might drop into the food. The knife 25 cannot leave the metal being cut since it is held in position by the cutting resistance. Since the rim of the can is removed, the contents can be easily and completely removed. In general the construction is 30 simple, inexpensive, sturdy, and easy to manipulate.

I claim as my invention:

1. A can opener having, in combination, a support having a prong on one end adapted 35 to pierce the center of the can cover and to hook underneath the cover when said support lies next to the cover, a carrier slidably mounted on said support, a lug formed on said carrier and adapted to fit over the inside of the end rim, a rotary knife pivotally mounted on the underside of said support, and means for holding said knife in cutting 40 engagement with the side of the can.

2. A can opener having, in combination, 45 a support having a pointed bent end, a carrier slidably mounted on said support and having a depending lug adapted to fit over the inside of the end rim of the can, a lever

pivotslly mounted on the underside of said carrier, a knife rotatably mounted on said lever adapted to be swung into cutting engagement with the outside of the can next to the rim, and means on said lever for holding said knife in cutting position.

3. A can opener having, in combination, 55 an elongated supporting member, a carrier slidably mounted on said member, a depending lug on the end of said carrier for engaging the end rim of the can to limit the outward movement of said carrier on said member, and a knife pivotally mounted on said carrier and adapted to be swung on said carrier into cutting engagement with the outside of the cylindrical wall of the can, said lug and said knife serving to hold 60 said carrier in position during the cutting operation.

4. A can opener having, in combination, a rod having a bent pointed end adapted to engage the cover and act as a pivot when 70 said rod lies next to the cover, a movable knife support on said rod, a lever on said support, a rotary knife pivotally mounted on said lever, a lug on said lever for limiting the pivotal movement of said lever in one 75 direction when said knife is in cutting engagement with the side of the can, and means for holding said support in position on said rod.

5. A can opener having, in combination, 80 an elongated rod having a prong for engaging the can cover and acting as a pivot for said rod, a carrier slidably mounted on said rod, a lever on the underside of said carrier, a rotary knife on one end of said lever, an actuating arm on the other end of said lever, a lug on said carrier for positioning the latter on said rod relative to the end rim of the can, and an upstanding lug on said lever bent at its upper end to extend over 85 said rod when said knife is in cutting position.

In testimony whereof, I have hereunto affixed my signature.

FREDERICK DREYER.
